COOKING GRILL

Robert M. Bryan, Birmingham, Ala., assignor to Atlantic Stove Works, Inc.

Filed July 24, 1969, Ser. No. 18,391

Term of patent 14 years

Int. Cl. D7—02

U.S. Cl. D81—10

Fig. 1

Fig. 2

FIG. 1 is a perspective view of a cooking grill showing my new design; and

FIG. 2 is a perspective view showing the opposite side of the grill proper from that shown in FIG. 1, the remainder of the cooking grill being omitted for the sake of clarity.

The characteristic feature of my design resides in the grid portion of the cooking grill.

I claim:

The ornamental design for a cooking grill, as shown and described.
